UNITED STATES PATENT OFFICE.

HENRY E. BILLMAN, OF ST. LOUIS, MISSOURI, ASSIGNOR TO INDUSTRIAL TRACK CONSTRUCTION COMPANY, OF ST. LOUIS, MISSOURI, A CORPORATION OF MISSOURI.

RAILWAY ACCESSORY.

1,389,617.

Specification of Letters Patent. Patented Sept. 6, 1921.

Application filed January 17, 1921. Serial No. 437,674.

To all whom it may concern:

Be it known that I, HENRY E. BILLMAN, a citizen of the United States, and a resident of city of St. Louis, State of Missouri, have invented an Improvement in Railway Accessories, of which the following is a specification.

This invention relates to a railway accessory, and with regard to certain more specific features, to a splice or reinforcing construction for use in connection with a bumping post.

Among the several objects of the invention may be noted the provision of a simple and inexpensive construction adapted for use with existing types of bumping posts, whether such posts are new or are already installed; the provision of a rugged and reliable device for repairing broken rails in such posts; and the provision of splice or reinforcing members readily applied to new or old posts, and not liable to derangement through severe service conditions. Other objects will be in part obvious and in part pointed out hereinafter.

The invention accordingly comprises the elements and combinations of elements, features of construction and arrangements of parts which will be exemplified in the structures hereinafter described and the scope of the application of which will be indicated in the following claims.

In the accompanying drawings, in which are shown one or more of various possible embodiments of the invention,

Figure 1 is a perspective;

Fig. 2 is a sectional elevation on the line 2—2 of Fig. 6;

Fig. 3 is a sectional elevation on the line 40 3—3 of Fig. 6;

Fig. 4 is a plan of one rail and the splice members associated therewith;

Fig. 5 is a similar view of the splice members *per se*; and

Fig. 6 is a side elevation of Fig. 4.

Similar reference characters indicate corresponding parts throughout the several views of the drawings.

Referring now more particularly to Fig. 1 of the accompanying drawings, there is illustrated a bumping post comprising an an-

chored support 1 for the bumping block 2 and for the inclined ends of the two rails 3, 4. The horizontal portions 5, 6 of these rails are at the proper gage for the operation 55 of cars thereon. At about the middle of the splice or reinforcing members 9, 10 the rails are bent inwardly and upwardly, to the extent required by the particular design of post. Each of the four members 9, 10 is 60 anchored to a buried tie or "dead man" 11 by means of bolts, of which the bolts for the members 9, 10 for the near rail are illustrated at 13 in Fig. 1.

As is shown more in detail in Figs. 2 to 65 6, the members 9, 10 are fitted to either side of a rail, the rail having been drilled at eight places (four on the horizontal part 5, 6 of the rail and four on the inclined part 7, 8) to receive bolts 17 extending through 70 registering apertures in the rail and in the two members to secure them firmly together.

As indicated in Figs. 1, 4, 5 and 6, the outer members 9, that is, the member on the near side of the near rail 4 and the one on 75 the far side of the far rail 3, are identical, and the other or inner members 10 are also identical. A complete equipment thus consists of two outer members 9 and two inner members 10, with the requisite bolts, in this 80 instance sixteen bolts 17 for securing the members to the rails, and four bolts 13 for securing such members to the dead man 11. In applying the splice members to the rails in Fig. 1, the right ends (Fig. 5) of the 85 members applied to the near rail 4 (Fig. 1) would be horizontal, and the left ends (Fig. 5) of the members applied to the far rail 3 (Fig. 1) would be horizontal.

The members 9, 10 each include vertical 90 portions 19 fitting against the web 21 of the rail, and lower portions 23 longitudinally recessed to fit the base 25 of the rail. At each point where a bolt 17 is located, a boss 27 (Fig. 2) is formed on the vertical portion 95 19 to give adequate surface of contact between the splice member and the rail and to give a plain shearing stress upon the bolt. The remainder of each side portion 19 is of substantially channel shape, as indicated in Figs. 3 and 5.

The members may be used in several ways.

First, in new or existing installations where the rails 3, 4 are each bent as in Fig. 1, the members are applied to such rails and secured to the dead man. Second, in existing installations where a rail is broken at the bend, the present invention makes unnecessary the provision of a new bent rail to replace it, as the only procedure needed is to saw off the horizontal and inclined parts of the rail, leaving a gap between them as indicated in Figs. 4 and 6, whereupon the members 9, 10 may be applied to the two rail parts and secured to the dead man. Third, in new installations no bent rail is required, but instead the horizontal part of each rail is laid so as to terminate at about the point 29 in Figs. 4 and 6 and the inclined part of each rail is of the proper length to terminate at about the point 31 in Figs. 4 and 6, whereupon the members 9, 10 may be applied to the two parts of each rail and secured to the dead man.

The invention is thus useful in a variety of ways, in connection with both new and existing bumping posts.

From the above, it will be seen that the several objects of the invention are realized, and other advantageous results attained.

As various possible embodiments might be made of the above invention and as various changes might be made in the embodiments above set forth, it is to be understood that all matter herein set forth or shown in the accompanying drawings is to be interpreted as illustrative and not in a limiting sense.

I claim:

1. In apparatus of the class described, in combination, a bumping device comprising an anchored support; horizontal and inclined rail lengths associated therewith; and means for strengthening said lengths, said means comprising a member fitting the outer side of both lengths, a member similarly fitting the inner side of both lengths, means for securing said members together and to both lengths, and means for anchoring both members.

2. In apparatus of the class described, in combination, a bumping device comprising an anchored support; horizontal and inclined rail lengths associated therewith; and means for strengthening said rails, said means comprising, for each rail, a pair of members fitting the web and around and beneath the base of both lengths, and adapted to be secured together and to the rail lengths.

3. In apparatus of the class described, in combination, a bumping device comprising an anchored support; a bumping block thereon; track rails bent upwardly and inwardly and secured to said support; and means for reinforcing said rails, said means comprising, for each rail, an outer reinforcing member having a vertical portion fitting

the outer side of the web of the horizontal and inclined portions of the rail and a lower portion fitting around and beneath the outer side of the base of the horizontal and inclined portions of the rail, an inner reinforcing member similarly fitting the inner side of web and base of the rail, means for securing said members together and to both portions of the rail, and means for securing said members to a dead man.

4. In apparatus of the class described, in combination, a bumping device comprising an anchored support; a bumping block thereon; rails inclined upwardly and inwardly and secured to said support; and means for securing said rails to the track rails, said means comprising, for each track rail, an outer splice member having a vertical portion fitting the outer side of the web of track rail and inclined rail and a lower portion fitting around and beneath the base of track rail and inclined rail, an inner splice member having a vertical portion fitting the inner side of the web of track rail and inclined rail and a lower portion fitting around and beneath the base of track rail and inclined rail, means for securing said members together and to the track rail and inclined rail, and means for securing said members to a dead man.

5. In apparatus of the class described, in combination, a pair of members adapted to fit upon the outer side of the web of horizontal and inclined track rail lengths and around and beneath the base thereof, and adapted to be secured together and to said lengths and to be anchored.

6. In apparatus of the class described, in combination, a pair of splicing or reinforcing members adapted to fit upon either side of the web of a track rail length and around and beneath the base thereof, and having portions extending at an angle to such rail, upwardly and inwardly, to fit upon either side of a rail length inclined to the first length and around and beneath the base of said rail length, means for securing said members together and to said rail lengths and to a dead man, said members being adapted for use interchangeably on either of the two track rails.

7. In apparatus of the class described, in combination, a pair of reinforcing members adapted to fit upon either side of the web of the horizontal portion of a track rail and around and beneath the base thereof, and having portions extending at an angle to such rail, upwardly and inwardly, to fit upon either side of the inclined portion of said rail and around and beneath the base thereof, and means for securing said members together and to said rail and to a dead man.

8. In apparatus of the class described, in combination, a pair of splicing members adapted to fit upon either side of the web of

a track rail and around and beneath the base thereof, and having portions extending at an angle to such rail, upwardly and inwardly, to fit upon either side of an inclined rail and around and beneath the base thereof, and means for securing said members together and to said rails and to a dead man, said

members being adapted for use interchangeably on either of the two track rails.

In testimony whereof, I have signed my name to this specification this 14th day of January, 1921.

HENRY E. BILLMAN.
